UNITED STATES PATENT OFFICE.

EDWARD B. ENTWISLE, OF JOHNSTOWN, PENNSYLVANIA, ASSIGNOR TO
THE JOHNSON COMPANY, OF KENTUCKY.

RAILROAD-CROSSING.

SPECIFICATION forming part of Letters Patent No. 447,130, dated February 24, 1891.

Application filed April 2, 1889. Serial No. 305,659. (No model.)

To all whom it may concern:

Be it known that I, EDWARD B. ENTWISLE, of Johnstown, in the county of Cambria and State of Pennsylvania, have invented a new 5 and useful Improvement in Railroad-Crossings, which invention is fully set forth and illustrated in the following specification and accompanying drawings.

The object of this invention is to provide, 10 in particular, a crossing for a street-railroad over or across a steam-railroad track, though of course the invention may be applied to the crossings of any railroad-track.

In the accompanying drawings, Figure 1 15 illustrates a crossing in plan constructed according to this invention. Fig. 2 shows the crossing in side elevation, being an end or side view of Fig. 1. Fig. 3 shows in plan, on an enlarged scale, one corner of the crossing 20 shown in Fig. 1, all the other corners being of similar construction. Fig. 4 shows Fig. 3 in end elevation.

In said figures the several parts are indicated by reference-letters, as follows:

25 The letter A indicates the rails of a steam-railroad track crossed by the street-rail track, indicated by the letters B b. The continuations b of the rails B will be hereinafter specially treated of. The letter C indicates a series of angle-ties, which hold the rails B b to their proper gage in the track; D, diagonal ties or stiffeners for the two rails B B. Said rails and the rails b b are indicated in cross-section, as shown at E E, Fig. 1. This section 30 of rail has a very shallow groove for the flange of the car-wheel to run in, and is known to the trade as a "switch-rail." Its depth of groove is only such that while the wheel-tread is bearing on the head of the rail the flange 35 is also bearing on the bottom of the groove. The car can therefore pass from a tread bearing on the head of the rail to a flange bearing in the groove without any jar occurring. At 40 the point F of the rail b the head and guard of the rail are each cut away. This cutting permits the wide wheel of a locomotive passing on the T-rails A to clear the crossing rail b without any jar, as it does not touch said rail. To insure this end it is preferable that the floor 45 F should be made slightly lower than the head of the T-rail A.

The interior rails B are made shorter than the full space between the T-rails A, so that sufficient space shall be left between said rails to let the wheel-flanges on the rails A pass 55 without touching the rails B. These intervening spaces are indicated in the drawings by the letters o. The cars crossing on the rails B b have therefore no jar while crossing except over said open spaces o, these spaces 60 being the only interruptions to the passage of the wheels over a level surface.

The angle-tie bars C not only retain the rails B b to the true gage of the track, but said ties are themselves also well secured to 65 the cross-ties of the steam-railroad by means of spikes, and as said tie-bars cross many of said cross-ties there is always greater certainty of a good and strong connection of the parts than is the case in crossings which depend upon only one tie for making the necessary connections of the parts.

It is important in a good crossing not only that the respective levels of the parts be provided for, but that they should be securely 75 maintained under the conditions of practical travel. The passage of heavy steam-cars on a steam-rail track effects frequent displacement of the rails A by depressing them in some cases and raising them by an up-ending 80 tendency in others. The rails b b should therefore be connected with the rails A, so that one set of rails may not move without the other, in order to preserve the same level at their crossing-points. This is effected by the 85 fitting-chocks G, secured to one side of the angle-ties C. Each of said angle-ties is preferably provided with holes throughout its whole length, so that if a rail b should come opposite to a joint in a rail A the fitting-chock 90 G may be set to clear such joint; but if not so set and if riveted to the angle-ties before the rails are laid the chock may be shifted to clear the joint in the rails A by simply cutting the rivets and reriveting or bolting the chock 95 in the desired position. Bolts instead of rivets may be used in the first instance to secure the chocks to the angle-ties C, in which case the chocks can be shifted without cutting any rivets. It is better, however, that said chock 100 be placed, if possible, where shown in the drawings. The interior rails B are shown in

the drawings unprovided with such chocks, although, if desired, such chocks can be also advantageously there applied, care being taken to so design the fitting-chocks as not 5 to obstruct the passage of the flange of the wheels using the rails A. The angle-ties C thus present, as shown, one face for the chock-fastenings G and one for the fastenings to the cross-ties of the steam-track. Said angle-ties 10 offer the further advantage of acting as good clean-cut bearings for the flooring or planking generally used at rail-crossings. The diagonal ties or tie-bars D act as additional stiffeners or braces to the angle-ties C. The rails B b 15 are riveted to the angle-ties C, as shown in the drawings, liners H being inserted under the rails B where necessary to regulate their level or height, and the ends of the rails b, which connect with the street-car track proper, 20 are preferably planed on an incline in their grooves to permit of the easy lift of the cars approaching the crossing in case the wheel-flanges of such cars are of unusual depth.

A principal advantage of employing the 25 section of rail b for this crossing is that, by planing its head and exposed guard away, a

large flat surface is left at its point of contact F with the steam-rail A, the usual method of filling up a partially cut-away groove in the crossing rail with a false plate or floor-plate 30 being thus obviated.

I do not claim the guard-rail B b, *per se*, as of my invention; but,

Having thus fully described my said improvement in railroad-crossings, as of my invention I claim—

1. In a railroad-crossing, a movably-fixed chock, as G, adapted to brace a crossed and crossing rail at their meeting point or junction by either lapping said junction or by 40 being set at one side of the same.

2. In a railroad-crossing, the combination of crossing rails, as B b, chocks, as G, and angle-tie bars, as C, for the purposes set forth.

3. In a railroad-crossing, the combination 45 of angle-ties, as C, and diagonal tie-bars, as D, for the purposes set forth.

EDWARD B. ENTWISLE.
